UNITED STATES PATENT OFFICE.

CHARLES F. FILOR, OF TRENTON, NEW JERSEY.

ICE-SKATE.

SPECIFICATION forming part of Letters Patent No. 617,649, dated January 10, 1899.

Application filed September 23, 1898. Serial No. 691,686. (No model.)

To all whom it may concern:

Be it known that I, CHARLES F. FILOR, of Trenton, in the county of Mercer and State of New Jersey, have invented a new and useful Improvement in Ice-Skates, of which the following is a full, clear, and exact description.

The object of my invention is to provide an improved lock for the heel and the sole clamps of a skate, the lock being exceedingly simple, durable, and effective and adapted through the medium of a lever for the final adjustment of the said heel and sole clamps.

A further object of the invention is to so construct the locking devices attached to the sole and the heel clamps that either of said clamps may receive an initial or broad adjustment without disturbing the adjustment of the other.

Another object of the invention is to so construct the runner of the skate that it will offer the least possible resistance to the ice.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the improved skate, in positive lines showing the clamps as closed and in dotted lines as open. Fig. 2 is a side elevation of the skate with the clamps closed. Fig. 3 is a longitudinal vertical section on the line 3 3 in Fig. 1 through the heel and sole plates and their clamps, the said section being likewise taken through the lock-links and lever connected therewith. Fig. 4 is a transverse section taken substantially on the line 4 4 of Fig. 1. Figs. 5 and 6 are detail views of supporting-pins for the adjusting mechanism, and Fig. 7 is a perspective view of a washer used in connection with the said pins.

The runner A is provided near the front with upwardly-extending standards 10 and 11, upon which standards the sole-plate 12 is secured, and at the rear the runner is provided with another standard 13, to which the heel-plate 14 is attached, the forward end of the heel-plate being provided with an upwardly-curved flange 14^a. In order that the

runner may have the least possible bearing on the ice, that portion of the runner which would be below the instep of the foot is upwardly curved, as shown at 15 in Figs. 2 and 3, so that this portion of the runner does not come in contact with the ice, but a firm bearing of the runner is obtained on the ice beneath both the sole and the heel plates. 55 60

Two sole-clamps 16 and 17 are employed, the said clamps being curved in opposite directions, so as to extend beyond opposite sides of the sole-plate, said clamps 16 and 17 being beneath the sole-plate and passing 65 through guides 17^a. The outer forward end of each of the sole-clamps is provided with an upwardly-extending flange 18, and the rear ends of the said clamps are adapted to meet, the end of one clamp being fitted to 70 turn on the end of the other clamp, and at the connected portions of the two clamps their inner faces 19 are straight or practically so.

A pivot-pin 20 is provided for the sole- 75 clamps. This pin is passed through the overlapping rear ends of the clamps and, as shown in Fig. 6, is provided with a head a, which is located above the upper surface of the clamps, a cylindrical surface a' immediately below 80 the head, around which the clamps turn, and a shank a², which extends beyond the under faces of the clamps, opposite surfaces of said shank being flattened, as is also shown in Fig. 6. 85

The heel-clamp 21 is provided at its rear end with upwardly-extending flanges 22 and at its center with a longitudinal slot 23, which extends from the rear end of the clamp to a point near its center, the said slot receiving 90 the rear standard 13 of the runner, and a bat-ten 24, attached to the heel-plate, serves as a guide for the heel-clamp.

A pin 25 is located at the forward end of the heel-clamp. This pin is provided with a 95 head b, as shown in Fig. 5, the head being countersunk in the upper face of the heel-clamp, and a cylindrical surface b' below the head contained within the opening in the heel-clamp, and a shank b², flattened at opposite 100 sides, which shank extends beyond the under face of the said heel-clamp. A lever 26 is adapted to operate the adjusting and locking devices for the clamps. This lever is shown

open in dotted lines in Fig. 1 and is mounted to turn around the upper reduced portion of a stud 27, secured to the arched portion of the runner and extending beyond the upper edge 5 thereof, as shown particularly in Fig. 4, and the lever is held in position on the stud by a cap-screw 28, which is screwed into the said stud.

In connection with the lever 26 two links 10 B and C are employed, the link B being adapted for connection with the heel-clamp and the link C with the sole-clamp of the 15 skate. The inner end 29 of each of the said links is curved, and the curved surfaces of the links are made to face one another, their 20 concaved edges being opposing edges. The shank or body 30 of each link is exteriorly threaded, and the curved portion of the link B is pivoted on a pin 31 at one side of the 25 fulcrum of the lever 26, while the curved portion of the link C is pivoted by a pin 32 at the opposite side of the fulcrum of the lever 26; but the pivotal connections between the links B and C and the lever 26 are out of 30 alinement with the center of the fulcrum of said lever, so that when the curved portions of the links are brought close together by the 35 movement of the lever 26 they will automatically lock themselves in such position.

30 The threaded shank of the link C is passed loosely through an opening in the shank a^2 of the pin 20, and washers 33 are loosely placed on the threaded shank of the link C, which 40 washers have bearing against the flat surfaces of the pin 20 and against the under surface of the sole-clamps. Lock-nuts 34 and 35 are 45 screwed upon the threaded shank of the link C, one to an engagement with each washer 33. It is obvious that by shifting the nuts 34 and 35 the throw of the sole-clamps may be 50 regulated, since the sole-clamps are moved to and from the sole by the movement of the aforesaid link C. The threaded shank of the link B is loosely passed through the shank b^2 55 of the pin 25, carried by the heel-clamp, and washers 36 are loosely mounted on the said threaded shank, engaging with the flat surfaces of the shank of the pin 25, and lock-nuts 37 and 38 are screwed upon the shank of 60 the link B to an engagement with said washers, whereby the throw of the heel-clamp may be regulated independently of the throw of the sole-clamps.

In fitting a skate to a shoe the heel and sole clamps are adjusted relatively to the heel 55 of the shoe and the side edges of the sole by the manipulation of the lock-nuts 34 and 35 and 37 and 38, the adjustment being so made that when the lever 26 is carried outward to open the clamps the shoe may be readily 60 placed on the sole and heel plates. After the shoe is in position on the skate the lever 26 is carried inward or toward the runner and the curved portions of the links are drawn together, thus drawing the clamps inward, as 65 shown in positive lines in Fig. 1; but when the lever is carried outward to open the clamps the curved portions of the links B and C are carried away from one another, as shown in dotted lines in Fig. 1. 70

Having thus described my invention, I claim as new and desire to secure by Letters Patent—

1. In a skate, the combination, with the heel-plate, the sole-plate, the heel-clamp and 75 sole-clamps, of a lever fulcrumed between the heel and sole plates, links pivoted to the lever, at opposite sides of its fulcrum, one lever being connected to the heel-clamp and the other lever being connected to the sole-clamps, 80 means for adjusting the throw of the heel-clamp and means for adjusting the throw of the sole-clamps, substantially as specified.

2. In a skate, the combination, with a heel-plate, a sole-plate, a clamp held to slide upon 85 the heel-plate, and oppositely-diverging clamps held to slide upon the sole-plate, the sole-clamps being pivotally connected at their rear ends, of a lever fulcrumed between the sole and heel clamps, adjusting-links connected one with the sole-clamps and the other with the heel-clamp, the inner ends of the links being oppositely curved and pivoted to the lever, one at each side of its fulcrum, the pivot-points of the links being out of the center of the fulcrum of the lever, and means, 95 substantially as described, for independently adjusting each link upon the clamp with which it is connected, whereby the throw of either the heel-clamp or the sole-clamps may 100 be separately regulated, for the purpose set forth.

CHARLES F. FILOR.
